JAMES D. BUTLER, OF LANCASTER, MASSACHUSETTS.

Letters Patent No. 92,938, dated July 27, 1869.

IMPROVEMENT IN BRAIDING-MACHINES.

The Schedule referred to in these Letters Patent and making part of the same.

To all whom it may concern:

Be it known that I, JAMES D. BUTLER, of Lancaster, county of Worcester, and State of Massachusetts, have invented a new and improved Braiding-Machine; and I do hereby declare the following to be a full description thereof, reference being had to the accompanying drawings, making a part of this specification.

This machine is of the class in which threads running from different spools are braided together, either upon a strand or core, or simply upon each other, by the proper motion being given to the spools.

To furnish better means of accomplishing this work than have heretofore been known, is the object of my invention.

In the accompanying drawings—

Figure 1 represents a top view of the machine;

Figure 2, a front view;

Figures 3, 4, and 5, different views of one of the travellers;

Figure 6, a view of the top of one of the travellers of a different form from the other;

Figure 7, an elevation, in part sectional, of a modified form of the drivers and travellers, &c.;

Figures 8 and 9, two elevations of a modified form of the travellers and tension-weights, &c.;

Figures 10, 11, and 12, an elevation and horizontal sections of a modified form of the drivers; and

Figure 13, an elevation of a modified form of the travellers and tension-weights, &c.

Figs. 1 and 2 are drawn to a scale one-half that of figs. 3, 4, 5, 6, 7, 8, 9, 10, 11, 12, and 13.

Although the machine is adapted to the use of eight travellers or spool-carriers, but two of these are shown, since they are sufficient to set forth the invention, and a representation of more would tend only to confuse.

In figs. 1 and 2 the travellers are shown without the spool, spool-catch, tension-weight, &c., these all being distinctly represented in figs. 3, 4, and 5.

In figs. 1 and 2—

A is the bed-plate;

B, the lower table;

C, the outer part of the upper table; and

C, the inner part of the upper table.

The connection between A and B is by F F' F' and the lower part of G.

Between A and C the connection is made by E E' and G.

The inner part C' of the upper table is supported from B by the upright C'.

Fastened to A are the studs D D' D'' D'', upon which the drivers turn.

The driver on the stud D is H H' H'', with the gear H'' attached.

In the driver-plates are slots h, which hold the necks a a' of the travellers.

The gear H₂ is fast upon the shaft H₁, which turns in the bearings A¹ and A.

When H₁ is turned, therefore, the drivers are turned through the gearing H₂, H'', H₃, &c.

The bottom ends of the travellers are shaped to run in the tracks b b b, &c., and b' b' b', &c., and have each a flange, which bears upon the upper surface of B, thus supporting the weight of the travellers.

The tracks would cut the plate B into separate pieces, were it not that the ribs b₂ b₃, &c., hold them together. It would answer, if preferred, to cut the tracks only part way through the plate, and dispense with the ribs b₂, &c.

The upper ends of the travellers are guided by the upper table C C'. Of course, the edges of the plates against which the travellers bear, keep them from getting out of their course on the one side. To keep them against these edges, however, some special provision is needed, and this is supplied by having the traveller tops hooked to catch upon the flanges c c c, or c' c' c' c', on the plates C C'. Half of the travellers run in the track b b b, and the others in b' b' b'. Those which, like the traveller I, run in b' b' b' b', are hooked to catch upon the ribs c' c' c' c', on the under sides of the plates C C'. Those, which like J, run in b b b, are hooked to catch upon the ribs c c c c, which are on the upper sides of C and C'.

The particular form I have given to the hooked traveller-tops, and to the flanges on the plates, may be made more plain by a reference to figs. 3, 4, 5, and 6.

In figs. 4 and 6, the plates are shown shaded, as in cross-section. The shape given is apparent from the drawing, in connection with the explanation already given.

The rib c'', under and opposite to c, is for the flange J'' on the traveller to bear against, to keep the traveller from lifting. It is not absolutely needed.

It will answer, and in some cases may be preferred, to have all the travellers catch upon ribs, on the same side of the upper tables like I, upon ribs c', on the under side, or like J, upon ribs c, on the upper side.

The traveller-top must be long enough to reach from the outer part C to the inner part C' of the table, so that in running, it may catch upon the one before it leaves the other.

With the traveller, as shown in figs. 3 and 4, the spool, the tension-weight, &c., are between the necks a a', against which the edges of the slots h, in the upper and lower driver-plates H'' H', respectively bear.

In fig. 7 there is also shown a modified form of the driver H' h₁ h₂ H₃, such as allows the abandonment of the bed-plate A, figs. 1 and 2, and, in general, a simpler construction, the lower table B serving as bed-plate, as well as table.

The studs D, &c., are fastened to B, as may also be the standards E E' and the post G.

Instead of the gear H'' and the driver-plate H'', there may be used the gear H₃, with the slots h in it.

This gear has a double row of teeth, h_1 representing the upper, and h_2 , the lower row.

The space between them is represented at h_3 . The teeth in the one row come opposite the spaces in the other.

It would answer to have only one row of teeth, in some cases.

The sleeve h_4 , h_5 turns upon the stud D, and H¹ and H² are fastened to it firmly and turn with it. This sleeve may be a piece of the brass tubing which has now become an article of regular manufacture, and which it may be more convenient to use than to make a sleeve especially for the place.

Another form of the driver is shown in figs. 10, 11, and 12, the former being an elevation, and the others, sections across 1 2.

The drawings need but little explanation.

The teeth in the one gear may be set to come opposite to the spaces in the other, as seen in a line parallel with the axis of the driver, as represented; or the teeth in the two may be in the same line parallel with the axis.

The flanges H⁴ are to give the proper shape to the edges of the slots, which bear against the traveller-neck.

The details of the traveller and its accompanying parts will be understood from figs. 3, 4, and 5.

The spool K is held in place by the spindle K'.

The upper end of this spindle is forked, to fit around the part J'' of the traveller, and its lower end is supported on the horn J'. It may be taken out by being raised, and having its lower end swung over the horn.

The piece L, guided upon the rod O, at L' and L'', catches upon the pins k k, &c., on the spool, to keep the latter from turning freely.

The end of L is guided between the body of the traveller and the hook L'''.

The rod O is supported by the ears M M'.

The tension-weight P, as well as the catch L, already referred to, slides upon this rod.

In one side of P there is a groove, P', in which runs the wire Q' Q Q'', and the edge of the rib R.

The shoulder or wing R' limits the upward movement of the weight. The wire Q' Q Q'' serves as a sort of hook, around which the thread runs. As this wire is hooked under the weight, the latter may be raised by it.

The thread is easily traced in the drawing, running from the spool through the hole S; from S round Q Q'', and from thence through the hole S' S''. As the traveller runs in its track around the machine, approaching to or receding from the braiding-point, the thread draws and slackens alternately, first raising Q' Q Q'', and through it, P, and then allowing them to fall.

When more thread is needed in the running of the machine, the end Q' of the wire is lifted against the ear L'' of the spool-catch, and raising the catch from a pin, k, allows the spool to turn and let off the thread required. The shoulder R' is so placed as to stop the weight, and prevent its striking the spool-catch.

Heretofore it has been customary to have the catch raised by the striking of the weight against it. To this, however, there has been the very serious objection that in any attempt at rapid running of the machine, the uncontrolled momentum of the weight, when suddenly raised, has carried the weight against the catch, so as to lift the latter and let off thread from the spool, when no more was needed or could be taken care of, the effect of which is to make the thread so slack that good braid will not be made. This defect has very narrowly limited the speed of braiding-machines.

Now, inasmuch as in my arrangement the wire Q' Q Q'' slides freely in the groove P' of the weight, so that the end Q' may drop down upon the weight, and

the weight itself cannot touch the catch or push the wire against it, the letting off of the thread is altogether beyond the reach of any disturbing influence from the jumping of the weight.

The momentum of the wire which acts upon the catch is of no practical account, because the wire may, from the nature of the case, be very light, but the weight must be heavy enough to give the proper tension to the thread, and with the action of the weight, as drawing upon the thread, my plan in no way interferes, the modification it introduces being only in connection with the jumping of the weight. This part of my invention, by which the thread can act upon the spool-catch, while the weight cannot, has been found in practice to be of great consequence.

Figs. 7, 8, 9, and 11, give modified forms of the part of my invention having reference to the action of the thread upon the spool-catch.

The traveller in fig. 7 is in general so similar to that used in what is commonly known as the "English braider," that it is sufficient for me to explain the modifications which I have introduced.

Heretofore the wire hook T' T'' has been fast to the weight T T', so that it was virtually a part of it. The catch T'' was therefore raised by the striking against it of what was virtually the tension-weight.

I give to T' T'' a sliding motion in the weight, so that while the end T'' is hooked, so that it cannot draw out of the weight, it may yet slide down upon the weight until T'' is in contact with the top of the weight.

The pin T, which is fastened to the weight, runs in a groove, h' h'', in the tube h, h''. Heretofore this pin has been so set that the weight could rise high enough to lift the catch T'' out of the notch in the spool. I set the pin so that the weight cannot act upon the catch.

The shoulder at h' corresponds with the shoulder R' in figs. 3, 4, and 5.

The sliding of T' T'' in the weight is like the sliding of Q' Q Q'' in its weight.

In figs. 8 and 9 the tension-weight is represented by U U' u u', and the spool-catch by U'' U' U''. In this form of the invention it will be seen there is no wire hook corresponding to Q' Q Q'', the thread taking hold directly of the weight, and acting directly upon the catch.

It will be clear from the drawing that the thread runs from the spool through the hole u', then over the corner of the weight at u, then across the hole U', then through the hole u', and then through u'' to the braiding-point.

The hole U' is so large that it will slide right over the part U'' of the catch, without raising it, but while the thread is drawing it is stretched across the hole from u to u', so that it will, when it has lifted the weight sufficiently, strike against the end U'', and raise the catch out of the notch in the spool.

If the thread is slack, as it will be when the weight jumps, it will not be stretched across the hole U', and the catch will not be raised.

The weight is prevented from striking the catch by the screw u' in the upright.

The spool is represented as above the upper-tables, as in the form shown in fig. 7.

In fig. 13, the wire W' W'' W''' W' W'', which is raised directly by the thread, runs in the notches X of the spool, and serves as the catch. It allows the spool to turn when the corner W'' is raised above X.

The wire is guided by being wound around W W', at W' and W'', and having its end W' run in the groove W, W'.

The weight W is supported upon the wire as shown.

The piece W, w' w is fastened to W, W', by the set-screw w'.

The thread runs from the spool first through w, then through W'', and then through w' to the braiding-

point, the space between the top of W and the part W' of the catch being so great as to allow considerable jumping of the weight without its striking the catch.

I have not shown any stop on W₁ to limit the upward movement of the weight, though I think such is desirable not only for the protection of the catch, but because the weight, in rebounding from it, will the sooner fall back to its place, to act in keeping the thread at its proper tension.

In some cases it may be desired to arrange the mechanism with a spool-catch, having a horizontal movement out of the notches of the spool.

These several tension-weight and spool-catch arrangements are quite varied in detail, and yet are but specimens of the different shapes which my invention may take, and they might be multiplied almost without limit; but I believe that enough variety in its forms of application has been shown to make clear the comprehensiveness of this part of my invention, which includes the mechanism in which the spool-catch, separate from the weight, is operated by the thread acting either directly upon it or through a part distinct from the tension-weight proper.

In figs. 3, 4, and 5, the tube N encloses loosely the rod O O. It is supported upon the ear L" of the spool-catch, and on being raised, it will strike against the ear M of the traveller.

I have found that even when the spool-catch is protected from the action of the tension-weight, as already explained, it is yet liable to be jarred out of the notches of the spool in the rapid running of the machine. No increase in the weight of the catch in the least corrects this trouble; but with a weight resting upon the catch, which shall be free to rise without carrying the catch with it, the difficulty is, I find in practice,

entirely removed. Any tendency the catch has to jump seems to be altogether transmitted to the weight which rests upon it. It is of course necessary that the weight should be heavy enough to receive this impulse entirely. If made extremely light, it would not be of service. The tube N serves as this weight. It is made so short as not to prevent the catch from rising clear of the pins on the spool. It in no way interferes with the raising of the catch by the steady force exerted upon it when it should be raised to let off the thread from the spool, except that it makes so much additional weight to be raised. This combination of the spool-catch, and the weight supported upon it, is not dependent upon the exact forms of these parts.

The improvements included in this invention are equally applicable to the different varieties of braiding-machines used, including those for making flat braid. The modifications required will be obvious to any one familiar with such machines.

What I claim as my invention, and desire to secure by Letters Patent, is—

1. The hooked traveller-tops, substantially as described.
2. The combination of the hooked traveller-tops with the upper table, substantially as described.
3. The combination of the spool-catch with its weight, substantially as described.
4. The means for operating the spool-catch by the thread, undisturbed by the jumping of the weight, substantially as described.

JAMES D. BUTLER.
